UNITED STATES PATENT OFFICE.

BYRON B. GOLDSMITH, OF NEW YORK, N. Y.

DESIGN FOR A LEAD-PENCIL.

SPECIFICATION forming part of Design No. 28,558, dated May 10, 1898.

Application filed February 8, 1898. Serial No. 669,594. Term of patent 14 years.

To all whom it may concern:

Be it known that I, BYRON B. GOLDSMITH, a citizen of the United States, and a resident of New York, in the county and State of New 5 York, have invented and produced a new and original Design for Lead-Pencils or such Similar Analogous Articles for which it may be Adapted, of which the following is a specification.

10 The drawing represents a lead-pencil, showing my design.

The leading or material feature of the design consists in closely-arranged discontinuous depressions A—that is to say, small 15 cavities—in the surface of the mantle of the lead-pencil.

The total effect of the design upon the observer is that of a multitude of discontinuous cavities covering the surface of the lead-pencil; but a closer inspection reveals that these 20 cavities are arranged on the lines of variously-pitched helices.

What I claim is—

The design for a lead-pencil substantially as herein shown and described. 25

In testimony whereof I have signed my name to this specification in the presence of two subscribing witnesses.

BYRON B. GOLDSMITH.
